Primary Examiner — Clare E Heflin(74) *Attorney, Agent, or Firm* — Tucker Ellis LLP(57) **CLAIM**

The ornamental design for a lamp, as shown and described.

DESCRIPTION

FIG. 1 is a perspective view of a lamp showing my new design.

FIG. 2 is another perspective view thereof.

FIG. 3 is a front view thereof, a rear view of the lamp being a mirror image of the front view.

FIG. 4 is a right side view thereof.

FIG. 5 is a left side view thereof.

FIG. 6 is a top view thereof; and,

FIG. 7 is a bottom view thereof.

The broken lines are for the purpose of illustrating portions of the lamp and form no part of the claimed design.
